Ira L. Nickerson*

UNITED STATES PATENT OFFICE.

RANSOM W. DAVENPORT, OF DETROIT, MICHIGAN, ASSIGNOR TO CHICAGO PNEUMATIC TOOL COMPANY, OF NEW YORK, N. Y., A CORPORATION OF NEW JERSEY.

PROCESS OF AND APPARATUS FOR HEAT TRANSFER.

Original application filed September 25, 1925, Serial No. 58,558. Divided and this application filed October 9, 1925. Serial No. 61,390.

This invention relates to an improved process of and apparatus for transferring heat, applicable either to heating or to refrigeration, but set forth herein in its application to refrigeration.

Among the objects of the invention are to provide a system of heat transfer which can be operated continuously, which has no easily deranged, complicated or delicate apparatus, which does not require the production of high pressures, and in general to simplify and to improve prior processes and apparatus.

In one aspect the invention consists in a process of producing thermodynamic effects resulting from the separation of a vapor from a liquid and from the reabsorption of the vapor in the liquid, somewhat after the manner of the so called absorption processes but with the difference that the present process operates continuously with the phase changes occurring simultaneously in different parts of the system which is of the closed cycle type. An important feature of the process is that the fluid stream which is circulated through the system contains both a gaseous and a liquid component. The fluid path of the system includes two bodies of liquid into which the gaseous component of the circulated fluid is expanded in succession and into which the liquid component merges temporarily.

The invention further comprises suitable apparatus for practicing the process. The working substance used may be a substance normally liquid at common or room temperatures and atmospheric pressures which separates as a "dew" in the case of homogenous liquids such as ethyl oxide or chloride, or may be absorbed into a weaker solution in case the chosen working substance is a complex liquid such as ammonium hydroxide.

In order to illustrate the invention a preferred embodiment thereof is disclosed in the accompanying drawing, the single view of which is diagrammatic, certain of the parts being broken away to indicate the movement of the fluids. The drawing illustrates a type of apparatus adapted to apply the improved process by bringing into contact with a relatively stationary body of liquid in the refrigerating zone a high velocity gaseous cur-

rent which weakens the liquid by removing vapor therefrom and conducting the vapor together with a limited quantity of the weakened liquid to a second body of liquid in the heating zone where the liquid is strengthened and whence a limited amount of the strengthened liquid together with the gaseous component of the circulating fluid returns again to the refrigerating zone. Liquids of the type of ammonium hydroxide, consisting of solutions or loose combinations of a gas and a liquid, are preferably employed partially to fill the system and the remainder of the system is filled with a gas substantially inert to and insoluble in the liquid. In the case of ammonium hydroxide air may be used as the inert gas.

In the drawing a vessel 11 which may take the form of a coil of pipe, as shown, is disposed in the refrigerating or heat absorbing zone and a second vessel 15 serves as the condenser or heat ejector, it being understood that the latter may be cooled in any well known manner as by a current of air passing thereover. These vessels are filled with the working liquid, such for example as ammonium hydroxide. The two vessels are connected to form a closed system of suitable conduits leading from the top of one to the bottom of the other. The connection from the heat absorber 11 to the heat ejector 15 comprises pipe 12, pump 13, and pipe 14. A single pipe 16 connects the chamber at the top of vessel 15 to the bottom of vessel 11, the outlet of pipe 16 being preferably restricted at 17 to impart velocity to the fluid passing therethrough. Pipes 12 and 16 are arranged to form a heat exchanger, as indicated, by passing pipe 16 for a distance within pipe 12. The parts of the system not filled with liquid contain a gas inert to and insoluble in the liquid and the components thereof, such as air. The pump 13 may be of any well known type adapted to handle gas and liquid, such for example as the Nash "Hytor".

In operation the pump 13 draws from the refrigerating vessel 11 and its pipe 12 ammonia vapor, air and a limited amount of ammonium hydroxide weakened by the loss of the ammonia vapor, the extracting of vapor producing a reduction of tempera-

ture in vessel 11. The pump ejects the stream of gas, vapor and weakened liquid at a somewhat higher temperature and pressure into pipe 14 whence the stream expands up through vessel 15 where its heat is given up with the result that the vapor is reabsorbed by the weakened liquid which accompanied it and by the liquid in vessel 15 which is thereby strengthened. The inert gas which has bubbled up through the liquid into the chamber above vessel 15 together with any vapor which may remain passes into pipe 16 along with the overflow of strong ammonium hydroxide from vessel 15. This stream of moving fluid which is largely inert gas and strong ammonium hydroxide with a slight amount of vapor is cooled by thermal contact with the cold fluid from vessel 11 by passage through the interchanger 12, 16 and expands at high velocity through the restricted nozzle 17 into the body of ammonium hydroxide in vessel 11. The expansion of the inert gas into vessel 11 produces violent agitation or ebullition and a rapid release of vapor not only from the strong ammonium hydroxide which accompanied the gas through the nozzle but also from the body of the liquid in vessel 11 which becomes progressively weakened by this loss of vapor as the top of the vessel is approached, heat being absorbed by member 11 as the result of such vaporization. This completes the cycle.

From the above it will be apparent that the improved process of transferring heat herein disclosed requires simple apparatus, easy to install and economical to operate, that the pressures maintained in the system vary only slightly from atmospheric pressures, and that the same circuit is utilized for producing movement of the liquid component of the refrigerant progressively from the zone of weak liquid to that of strong liquid and vice versa as is used moving the gaseous component of the working substance through its cycle.

The producing of the refrigerating effect in chamber 11 through the expansion of a compressed, inert gas accompanied by liquid refrigerant through a restricted opening is disclosed and generically claimed in my copending application Ser. No. 15,172 filed March 12, 1925. The method of effecting heat transfer by passing an inert gas in succession through spaced bodies of liquid in a closed cycle so as to produce an endothermic effect in one body and an exothermic effect in the other is disclosed and generically claimed in my copending application Ser. No. 58,558 filed Sept. 25, 1925, of which the present application is a division.

I claim as my invention:

1. The thermal process which comprises passing a current of inert and insoluble gas through two bodies of liquid in succession

in a closed cycle, and successively compressing and expanding said gas during and between its passages through said bodies while removing heat from one and supplying heat to the other of said bodies, meanwhile passing liquid in limited amount through the same cycle. 70

2. The thermal process which comprises disposing a solution of a working substance and a liquid in spaced bodies, passing a gas substantially inert to and insoluble in said substance and said liquid through said bodies in succession in a closed cycle, compressing said gas before and during its passage through one body and removing heat from that body, expanding said gas before and during its passage through the second body and supplying heat to that body, and meanwhile passing the solution in limited amount through the same cycle. 75 80 85

3. The thermal process which comprises disposing ammonium hydroxide in spaced bodies, continuously weakening one body by expanding an inert gas therethrough to carry away ammonia vapor and heat therefrom, and continuously strengthening another body by compressing said vapor-laden gas thereinto again to place said ammonia in solution and liberate said heat, and meanwhile effecting circulation of the ammonium hydroxide by moving a limited quantity of the same along with the vapor-gas stream. 90 95

4. The thermal process comprising placing a solution of ammonia gas in water in proximity to the thing to be cooled, forcing a current of a second gas, substantially cool, inert to ammonia and insoluble in the solution, into and through the solution to release ammonia gas and to absorb heat, forcing the mixture of inert gas together with the ammonia gas detached from the solution along with a limited quantity of the solution weakened by the detaching of the ammonia gas into and through a second body of the solution in proximity to the thing to be heated, thereby causing the vapor to be reabsorbed by said second body of solution and to give up heat, and cooling the inert gas issuing from said second body and conducting it together with a limited quantity of the solution strengthened by the absorption of the vapor to the first body of solution thereby completing the cycle. 100 105 110 115

5. The process of producing refrigeration which comprises forming a closed circuit containing spaced bodies of liquid, forcing a gas inert to and insoluble in the liquid to pass continuously through said circuit to carry away vapor of the liquid from one body which thereupon absorbs heat and to cause absorption of the vapor by the second body with ejection of heat, and moving a limited quantity of liquid from body to body along with the vapor-gas stream. 120 125

6. The continuous absorption process of 130

transferring heat which comprises disposing spaced bodies of a liquid containing a working substance in solution in a closed fluid circuit and utilizing as a vehicle for the 5 working substance a gas, substantially inert to and insoluble in the working substance, and in and to its liquid solution, by forcing said gas continuously to traverse said circuit into and through said bodies of the liquid 10 solution of the working substance thereby withdrawing the vapor of the working substance from one body with an endothermic effect and restoring said vapor to solution in said other body with an exothermic effect, 15 and causing movement of the solution in the same cycle by passing a limited amount thereof from one body to the next along with the gaseous stream.

7. The thermal process which comprises 20 forcing a mixture of a vapor and an inert and insoluble gas along with a liquid solution of said vapor through a closed cycle, and maintaining a difference in pressure between spaced portions of said cycle thereby 25 to produce different thermodynamic effects in said cycle as a result of the variations in the vapor content between the vapor gas stream and the accompanying liquid solution stream.

8. Apparatus for transferring heat comprising spaced vessels for containing a liquid working substance, means connecting said vessels to form a closed fluid path, and a single pump for forcing the circulation through 35 said path in one direction of a fluid stream comprising gas, vapor and liquid, the last two components of said stream being provided by the working substance contained in said vessels, the connections between the vessels being such that gas cannot be trapped 40 at any point.

9. Apparatus for transferring heat utilizing a volatile liquid, a relatively non-volatile liquid, and an inert gas comprising spaced 45 vessels, conduits connecting the top of each vessel to the bottom of the other to form a

closed circuit and to prevent the trapping of gas at all points, said vessels being adapted to be filled with a solution of said liquids and the remainder of the circuit being filled 50 with said gas, and means for forcing through said circuit in one direction a stream of said gas, vaporized liquid, and said solution to produce an endothermic effect in one vessel and an exothermic effect in the other. 55

10. Apparatus for transferring heat utilizing ammonium hydroxide and an inert gas comprising spaced vessels, conduits connecting the top of each vessel to the bottom of the other to form a closed circuit and to prevent the trapping of gas at all points, said vessels being adapted to be filled with said ammonium hydroxide and the remainder of the circuit with a gas, and a single pump arranged to force through said circuit a stream 65 composed of said gas, ammonia vapor and ammonium hydroxide to produce an endothermic effect in one vessel and an exothermic effect in the other.

11. Apparatus for transferring heat, utilizing a liquid, a gas having an affinity for said liquid, and a second gas substantially inert to and insoluble in said liquid and said first gas and in the solution of the two comprising a closed system having spaced vessels 70 for containing the solution of the liquid and the first named gas, a connection from the top of one vessel to the bottom of the other, a pump in said connection, and a connection from the top of the second vessel to 75 the bottom of the first, the second gas being adapted to be disposed in said connections, said pump being arranged to circulate through said system and up through said vessels a stream formed of said gases and a 80 limited amount of said solution, said connections permitting continuous movement of the circulating stream and preventing the trapping of the gaseous portion thereof. 85
